UNITED STATES PATENT OFFICE

LOUIS J. RECKFORD, OF NEW YORK, N. Y.; LOUISE KING RECKFORD, JOHN KING RECKFORD AND LOUIS J. GRUMBACH, EXECUTORS AND TRUSTEES OF SAID LOUIS J. RECKFORD, DECEASED, ASSIGNORS TO AMERICAN LEAD PENCIL COMPANY, OF HOBOKEN, NEW JERSEY, A CORPORATION OF NEW YORK

ERASER ATTACHMENT FOR LEAD PENCILS

Application filed June 19, 1926. Serial No. 117,014.

This invention relates to improvements in rubber eraser attachments for lead pencils.

One object of the invention is to provide an eraser attachment for lead pencils such that the eraser will have a much longer lifetime than the circular rubber tip ordinarily used heretofore, a lifetime approximating that of the pencil itself, and to accomplish this result without the employment of adjusting devices for the rubber tip and without departing from the preferred cylindrical form of the latter.

A further object of the invention is to provide an eraser attachment of the above character which is adapted to furnish a maximum surface for erasing written or other matter with a minimum effort.

A further object is to provide an eraser attachment of the above character, simple in construction and producible at low cost, and in such form that it will not encumber or interfere with the use of the member to which it is attached.

These and further objects will be apparent from the following description, when considered in connection with the accompanying drawing, in which one embodiment of the invention is illustrated.

Referring to the drawing, Figure 1 is a perspective view; Fig. 2 is an elevation; and Fig. 3 is a longitudinal section.

In the drawing, the pencil with which the improved eraser attachment is associated is shown in dotted lines and indicated by reference numeral 5.

A ferrule is attached to the upper end of the pencil 5, and this ferrule comprises two chamber portions which are of different diameters, said chamber portions being concentric to a common axis and being connected by an annular shoulder 10, thereby forming an integral ferrule. The lower portion 6, which is of smaller diameter than the upper portion 7, embraces the top of the pencil 5 in a tight-fitting manner so that its rotation on the pencil is prevented. The length of the chamber portion 6 is sufficient to hold the ferrule securely in position on the pencil.

For the purpose of presenting a smooth

and uniform surface between the pencil and the ferrule, the top of the pencil may be cut away so that the outer surfaces of the pencil and ferrule lie flush with each other. A shoulder is thus provided on the pencil at the termination of the cut-away portion, and this shoulder serves to limit the downward movement of the ferrule on the pencil.

The upper chamber portion 7 of the ferrule, which is of greater diameter than the portion 6, serves to hold an eraser 8 in position. The length of the wall of the chamber portion 7 is sufficient to prevent the displacement of said eraser by providing enough support therefor so that it will not become dislodged by any lateral strain while it is being used. The annular shoulder 10 intermediate the chamber portion 6 and chamber portion 7 not only serves to unite those chambers, which are of substantially different diameters, into an integral ferrule, but serves also the purpose of more securely seating the eraser, and limiting its entrance into the chamber portion 7. The wall of the chamber portion 7 may be provided with a smooth bore or have screw-spun threads provided in its surface, as indicated by the numeral 9. For the purpose of insuring the retention of the eraser 8 in its container 7, cement or other adhesive may be employed; it being a feature of the present invention that the eraser be permanently set in its container and that no adjusting means therefor be provided.

It will be obvious that, by means of the eraser attachment constructed as above described, it is possible to provide, in a simple and effective way and at minimum cost, a rubber pencil tip which will last as long as the useful lifetime of the pencil itself, and that it is possible thereby to achieve this long sought result without the use of adjusting devices and without departing from the preferred circular form of rubber.

It will also be obvious that by means of the improved arrangement, a maximum surface is provided which will permit the erasure of written matter with a minimum effort and without any interference with the function of the pencil or other member with which it may be associated.

From the foregoing, it is thought that the construction, operation and many advantages of the herein described and delineated invention will be apparent to those skilled in the art without further description, and it will be understood that various changes in the size, shape, proportion and minor details of construction may be made without departing from the spirit or sacrificing any of the advantages of the invention.

10 What is claimed is:

An article of manufacture consisting of an integrally formed ferrule whose wall is approximately concentric throughout to a common axis and which comprises an annular shoulder at the middle portion thereof, a pencil receiving portion of relatively small diameter extending from said shoulder in one direction and an eraser receiving portion of substantially larger diameter extending from said shoulder in the opposite direction; a pencil one extremity of which fits within said pencil receiving portion of said ferrule, being closely embraced by the wall thereof and permanently and immovably secured therein; and an eraser of substantially larger diameter than said pencil secured within and closely embraced by the wall of said eraser receiving portion of said ferrule and extending substantially beyond the outer extremity thereof.

30 In testimony whereof, I have signed my name to this specification this sixteenth day of June 1926.

LOUIS J. RECKFORD.
